Primary Examiner—M. N. Padozzi**Attorney, Agent, or Firm—Terry M. Germstein****[57] CLAIM**

The ornamental design for a decorated water container with carrying strap, as shown and described.

DESCRIPTION

FIG. 1 is a front, top and side perspective view of the decorated water container with carrying strap showing my new design;

FIG. 2 is a front elevational view thereof, with the strap stretched outward;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom plan view thereof.

The broken line showing of surface indicia of scorpion symbology in FIGS. 1, 2, 3, 4 and 5 is for illustrative purposes only and forms no part of the claimed design.
